UNITED STATES PATENT OFFICE.

ALBEN E. LUNDELL, OF CHICAGO, ILLINOIS, AND EDGAR H. CLARK, OF RICHMOND HILL, NEW YORK, ASSIGNEES TO WESTERN ELECTRIC COMPANY, INCORPORATED, OF NEW YORK, N. Y., A CORPORATION OF NEW YORK.

TELEPHONE-EXCHANGE SYSTEM.

Application filed June 9, 1920. Serial No. 387,531.

To all whom it may concern:

Be it known that we, ALBEN E. LUNDELL and EDGAR H. CLARK, citizens of the United States, residing at Chicago, in the county of Cook and State of Illinois, and at Richmond Hill, in the county of Queens and State of New York, respectively, have invented certain new and useful Improvements in Telephone-Exchange Systems, of which the following is a full, clear, concise and exact description.

This invention relates to telephone exchange systems in which connecting operators are employed for extending connections, with indicating mechanisms at such operators' positions to identify the designations of desired lines.

In systems where certain offices are equipped with mechanical switching apparatus, whereas other offices employ manual operators for establishing connections, it is found desirable that the manual operators be given the information required for them to extend or complete connections incoming from the mechanical office without the necessity of communicating orally with the calling subscriber or with other operators. To this end, each operator's position, in the manual office, is provided with call indicator mechanism, including a set of number-indicating devices, which is operated automatically under the control of registering mechanism in the mechanical office to inform the manual connecting operator of the number and character of the required connection. It is customary, in arrangements of this character, to provide each trunk circuit incoming to an operator's position from the distant mechanical office with a signal lamp, the illumination of which advises the operator that a call is awaiting her attention on the corresponding trunk. At her convenience she associates the calling trunk with the common indicating mechanism at her position, and thereupon the wanted designation is set up and displayed before the operator, who proceeds to complete the connection.

Where no attempt is made to secure a uni-

formity in the distribution of calls to the several operators in an office of this character, it may frequently occur during busy hours of the day, that an excessive number of calls simultaneously appear on the trunks at any given operator's position, while at the two positions adjacent thereto only a comparatively few calls are awaiting attention. In order that the completion of calls shall not be unduly delayed on this account, provision is made whereby the adjacent operator on either side of a home operator's position may assist the home operator by attending to some of the calls at her position.

Accordingly, it is the object of this invention to provide, in a system of the foregoing character where operator's positions are each equipped with a group of trunks and an indicating mechanism, means whereby one operator may cause to be set up, on the indicating mechanism at her position, the designation of calls appearing on trunks at other operator's positions.

A feature of the invention relates to an arrangement whereby the current impulses incoming over the trunk circuit at a home operator's position, which normally serve to record the desired designation on the indicating mechanism at such position, may be directed to an adjacent position for the purpose of recording the designation on the indicating mechanism at said adjacent position.

Another feature relates to the provision of two assignment keys for each trunk circuit at an operator's position; one of which, when operated, associates the corresponding trunk with the indicating mechanism at said position and causes the incoming impulses to set such mechanism in accordance with the designation concerned; the other of which keys, when operated associates said trunk with the indicating mechanism at a different operator's position and causes the incoming impulses to record the designation on the mechanism at said latter position.

Still another feature relates to the provision of a signal individual to an incoming trunk which operates in one distinctive

manner when one of the aforementioned assignment keys is operated and in another distinctive manner when another assignment key is operated, thus indicating which 5 of two operators is attending to a call on a trunk and thereby lessening the possibility of calls being extended incorrectly.

These and other features of the invention will be more apparent from a consideration 10 of the following description and the appended claims.

Referring to the drawings, Figs. 1 to 10 inclusive, when arranged in the order illustrated in Fig. 11, disclose so much of a telephone system which embodies the invention, 15 as is necessary to an understanding thereof.

Fig. 1 shows the incoming end of an interoffice trunk circuit at a mechanical office and the details of a district selector switch 20 in which said trunk line terminates.

Fig. 2 shows in detail the circuits of an office selector switch in the mechanical office.

Fig. 3 shows a trunk finder switch, common to a plurality of incoming trunk circuits, for associating an idle register sender 25 with a desired trunk.

Fig. 4 shows a sender for controlling the operation of the selective switches, comprising a circuit changing sequence switch and 30 a group of counting relays.

Fig. 5 illustrates a plurality of sets of keys at an operator's position, and a series of corresponding registers arranged to be positioned under the control of said keys for determining the selective operations involved 35 in the extension of a connection.

Fig. 6 shows a switch and associated circuits for transmitting series of code impulses, according to the variable settings of 40 the registers, to operate a call-indicator mechanism at a distant office.

Fig. 7 shows in detail a trunk circuit incoming from the mechanical office to a manual operator's position in a distant office.

Fig. 8 shows a call-indicating mechanism at the manual operator's position arranged to be associated with any of the trunk circuits at such position and operated in response to the code impulses sent over a calling 45 trunk from the mechanical office.

Fig. 9 shows the selecting relays and numerical lamps of the call-indicator for visually informing the manual operator of the designation of a called line.

Fig. 10 illustrates diagrammatically a trunk circuit similar to that shown in Fig. 7, incoming from the mechanical office to an operator's position adjacent to the position at which the first mentioned trunk appears.

Below the horizontal broken line in this figure there is illustrated the call-indicator mechanism at the adjacent operator's position which is similar in all respects to the one shown in detail in Figs. 8 and 9.

Fig. 11 shows how the figures of the draw-

ing are to be arranged to connect the circuits of the several figures.

General description of system and apparatus.

In the establishment of a connection in the system, disclosed, three different offices are to be considered; a calling manual office, where the call first originates; the tandem mechanical office, through which the connection is extended by means of automatic switches; and the terminating manual office to which the connection is extended and the wanted designation automatically displayed before the operator therein, who thereupon completes the connection. The call having originated at the manual office (not shown) the operator therein communicates with the operator in the mechanical office by means of an order wire and requests the assignment of an idle trunk. The operator at the mechanical office assigns an idle trunk, such as trunk 100, 101, and depresses the individual assignment key 108. The depression of key 108 initiates the operation of the trunk finder shown in Fig. 3, which associates the register sender shown in Figs. 4, 5 and 6, with the assigned trunk. The operator in the mechanical office having been verbally informed of the name of the 95

desired office and the number of the called line in such office, proceeds to set up the designation on the keys at her position. The selective operations of the district and office switches, which jointly serve to select an outgoing trunk to any one of a plurality of distant offices, are controlled by the settings of the four registers 500, 510, 520 and 530. Each of the various combinations of settings that these registers may take, determines the 100 selection of a group of trunks leading to a particular distant office. For convenience, therefore, a single office key is provided to cause the setting of all four of the office registers. One of these keys 580 is shown with the necessary wiring, to determine a single setting of the office registers, while another key 581, which may determine a different setting, is diagrammatically illustrated. Obviously, as many of these keys would be 105 provided as are necessary to accomplish the required number of office selections. In addition to the office keys, the operator's position is equipped with four sets of numerical keys, ten keys in each set, for setting the 110 numerical registers 540, 550, 560 and 570.

After the operator has depressed the proper combination of office and numerical keys the district and office selectors are operated and the connection extended over 115 a trunk, such as 700, 701, to an operator's position in the desired manual office. The operator in the terminating office is informed that a call is awaiting her attention, by the illumination of a lamp individual to the 120

trunk circuit. As soon as the operator has completed the extension of such calls as may have previously been directed to her position, she attends to the call appearing on 5 the trunk 700, 701, by depressing the individual assignment key. The depression of this key operates to associate the call-indicator mechanism at her position with the calling trunk circuit. Code impulses are 10 then sent over the trunk in accordance with the settings of the numerical registers of the mechanical office to select the proper combination of numerical lamps. The illumination of the indicator lamps at the 15 operator's position informs her of the number of the called line and the connection is completed by inserting the terminating plug of the trunk circuit in the proper jack.

It may happen that due to the simultaneous appearance of a large number of calls at a given position, the operator is unable to attend to all the calls with the necessary dispatch. According to the principles of this invention, the adjacent operator on either side 25 is able to assist the home operator whenever she becomes overtaxed in her duties, by attending to some of the calls at the home position. For this purpose, each of the trunks at a position is provided with a team 30 assignment key. The adjacent operator, observing the presence of a larger number of calls at the home position than the home operator can conveniently handle, reaches across and depresses the team assignment 35 key of a calling trunk. The depression of the team key serves to associate the calling trunk at the home position with the call-indicator mechanism at the adjacent operator's position. The incoming code impulses 40 are, therefore, directed to the indicator mechanism at the adjacent or helping-out operator's position and the designation of the desired line displayed on the numerical lamps at such adjacent position. The adjacent 45 operator then seizes the plug of the calling trunk circuit at the home operator's position and inserts it in the jack of the called line. As will be more fully explained hereinafter, supervision of a call thus completed by an adjacent operator, remains 50 under the care of the home operator in the same manner as calls normally attended to by the home operator.

The district and office selectors shown in 55 Figs. 1 and 2 and the trunk finder shown in Fig. 3 may be of the same general construction as the switch shown and described in the patent to Craft and Reynolds, 1,123,696.

The several sequence switches shown 60 throughout the drawings may be of the same construction as the one described in the patent to Reynolds and Baldwin, 1,127,808. With the exception of Fig. 5, the sequence switches shown in the different figures of 65 the drawings control respectively all the

contacts contained in each of such figures. In Fig. 5, the contacts contained within the spaces set off by the vertical broken lines, are controlled respectively by the correspondingly located sequence switches. 70

Detailed description—disposition of call by the home operator.

Having thus briefly outlined the present system, a detailed description will now be 75 given of the operations concerned in the establishment of a connection. It will first be considered that the operator at the terminating manual office to whose position the connection is extended, is comparatively 80 unoccupied and able to attend to the call without the assistance of the adjacent operator. The call having been originated in a distant manual office and the trunk 100, 101 having been assigned for use, the operator in the mechanical office depresses the assignment key 108. A circuit is then completed from ground through the contacts of key 108, right-hand contact 109 (1), winding of sequence switch magnet 110, 90 to battery and ground. Sequence switch 110 moves out of its normal position 1 into position 3. In position 3 of sequence switch 110 a circuit is established from battery, through the winding of the trunk finder 95 sequence switch 310, right-hand contact 317 (1), conductor 329, lower right-hand contact 113 (3), upper right-hand contact 113 (3), back contact and left-hand armature of relay 111, upper left-hand contact 121 (2 to 17), lower right-hand contact 121 (1 to 12), to ground. The trunk finder sequence switch 310 leaves its normal position and advances into position 2. In position 2 of sequence switch 310, a circuit is 100 completed from battery, through the winding of the up-drive power magnet 320, contact 314 (2), back contact and left-hand armature of relay 311, to ground. Magnet 320 energizes and the brush shaft 312 of 105 the trunk finder is moved upward to select the set of terminals individual to the trunk 100, 101. When the test brush 307 of the trunk finder reaches the terminal 302, a circuit is closed from battery, through the winding of relay 311, left-hand contact 328 (2), brush 307, terminal 302, conductor 139, lower contact 122 (3), upper contact 122 (2 to 3), back contact and outer right-hand 110 armature of relay 111, upper left-hand contact 119 (2 to 11), lower left-hand contact 119 (2 to 4), to ground. Relay 311 attracts its armatures and opens the circuit of the up-drive power magnet 320, causing the brushes of the trunk finder to stop 115 in engagement with the desired set of terminals. Relay 311 locks up in a circuit from battery through the winding of said relay, right-hand contact 328 (2 to 17), right-hand armature and contact of relay 120 125 130

311, brush 309, terminal 304, conductor 141, lower left-hand contact 114 (2 to 16), upper right-hand contact 114 (2 to 12 $\frac{1}{2}$) to ground. Relay 311 also completes a circuit from ground through its left-hand armature and front contact, right-hand contact 315 (2), winding of sequence switch 310, to battery and ground. Sequence switch 310 moves out of position 2 and into position 6. In position 6 of sequence switch 310, a circuit is closed from ground, through contacts 313 (6), brush 308, terminal 303, conductor 145, left-hand contact 115 (3), right-hand winding of relay 111, to battery and ground. Relay 111 energizes and completes a circuit from battery, through the winding of sequence switch 110, lower left-hand contact 112 (3), upper right-hand contact 112 (2 to 12), front contact and left-hand armature of relay 111, upper left-hand contact 121 (2 to 17), lower right-hand contact 121 (1 to 12) to ground. Sequence switch 110 advances from position 3 into position 5, opening the circuit of relay 111, which thereby deenergizes. An idle register sender is now associated with the calling trunk circuit 100, 101.

The operator, having been informed over the order wire of the wanted designation, depresses the key 580, which determines the selection of the desired office. Furthermore, she sets up on her keyboard the numerical designation of the called line in that office. The several office and numerical keys at the operator's position are arranged to be retained in their actuated position by means of locking magnets 503, 513, 523, 533, 544, 554, 564 and 574. Assuming that the number of the wanted line is 4432, the operator depresses No. 4 key 543 in the thousands row, No. 4 key 553 in the hundreds row, No. 3 key 563 in the tens row and No. 2 key 573 in the units row. Assuming the code pertaining to office key 580 to be 1223, the contacts of this key are wired to contacts of the four office registers 500, 510, 520 and 530, closed respectively in positions 1, 2, 2 and 3.

As soon as the trunk finder sequence switch 310 reaches position 5, parallel circuits are completed through the windings of the registers 500, 510, 520, 530, 540, 550, 560 and 570, back contacts and right-hand armatures of the respective stop relays 501, 511, 521, 531, 541, 551, 561, and 571, to the common conductor 582, contact 326 (5 to 6), to ground. These registers are all energized in the circuits traced and commence to rotate. When register 500 reaches position 1, a circuit is closed from battery through the winding of relay 501, contact 502 (1), left-hand contacts of key 580, to ground. When register 510 reaches position 2, a circuit is closed from battery through the winding of relay 511, contact 512, (2), left-hand contacts of key 580, to ground. In position 2 of register 520, a circuit is closed from battery through the winding of relay 521, contact 522 (2), right-hand contacts of key 580, to ground. In position 3 of register 530, a circuit is completed from battery, through the winding of relay 531, contact 532 (3), right-hand contacts of key 580, to ground. Relays 501, 511, 521, and 531 energize in the circuits traced and open the operating circuits of the four office registers, causing them to stop in their respective positions. When the numerical registers 540, 550, 560 and 570 reach positions 4, 4, 3, and 2 respectively, similar circuits are closed through contacts 542, 552, 562 and 572, for the stop relays 541, 551, 561 and 571, and in a similar manner, the operation of these relays opens the circuits of the numerical registers, causing them to cease to rotate. With all the stop relays energized a series circuit is closed from ground, through the front contacts and left-hand armatures of said relays, conductor 583, lower right-hand contact 316 (6), winding of sequence switch 310, to battery and ground. Sequence switch 310 advances from position 6 into position 10. As sequence switch 310 passes through positions 7 and 8 a circuit is closed from ground contact 330, (7 to 8), conductor 584, through the windings of the holding magnets 503, 513, 523, etc. in parallel, to battery and ground. These magnets energize and release the depressed keys of the operator's keyboard. The registers do not restore, but remain in the position last used. In position 10 of sequence switch 310, a circuit is closed from battery, through the winding of the sender sequence switch 410, lower right-hand contact 407 (1), contact 331 (10), to ground. The sender sequence switch moves from its normal position into position 4.

The office and numerical designations are now recorded on the registers of the sender and the selective operation of the district and office switches may be proceeded with. Accordingly, the fundamental circuit for controlling the brush selection of the district switch is established as follows: battery, through the right-hand winding of relay 111, lower left-hand contact 118 (5), lower right-hand contact 118 (5 to 8), conductor 137, terminal 300, brush 305, upper contact 324 (10), winding of the stepping relay 400, contact and outer armature of the 0' counting relay 420, upper right-hand contact 403 (4), lower left-hand contact 403 (2 to 6), to ground. Relays 111 and 400 become energized in this circuit. Relay 111 completes a circuit from battery through the winding of sequence switch 110, lower left-hand contact 112 (5), upper right-hand contact 112 (2 to 12), front contact and

left-hand armature of relay 111, upper left-hand contact 121 (2 to 17), lower right-hand contact 121 (1 to 12), to ground. Sequence switch 110 advances into position 6. Relay 111 remains energized in position 6 of sequence switch 110 by means of a circuit from battery, through the right-hand winding, contact and inner right-hand armature of said relay, upper left-hand contact 118 (3 to 10), lower right-hand contact 118 (5 to 8), and thence to ground over the fundamental circuit as described. In position 6 of sequence switch 110 a circuit is closed from battery through the winding of the updrive magnet 127, lower right-hand contact 112 (6), upper right-hand contact 112 (2 to 12), front contact and left-hand armature of relay 111, upper left-hand contact 121 (2 to 17), lower right-hand contact 121 (1 to 12), to ground. The power magnet 127 energizes and causes the upward movement of the brush shaft 129. For each brush tripping position passed over by the brush shaft 129, the auxiliary brush 130 makes engagement with a metallic segment of the brush selecting commutator 132 and completes a circuit from battery, through the right-hand winding, contact and inner right-hand armature of relay 111, upper left-hand contact 118 (3 to 10), lower right-hand contact 123 (5 $\frac{1}{4}$ to 6), commutator 132, brush 130 to ground. The closure of this circuit maintains the energization of relay 111 and at the same time shunts out the stepping relay 400 in the fundamental circuit.

When stepping relay 400 first energizes in series with relay 111 it completes a circuit from ground through its contact and armature, lower contact 402 (4), conductor 585, contact 504 of register 500 closed in position 1, conductor 505, and thence to conductor 426 (Fig. 4) armature and back contact of the No. 1' counting relay 422, winding of No. 1 counting relay 423, to battery and ground. Relay 423 energizes and closes a circuit from battery through the windings of relay 423 and 422, contact and armature of relay 423, contact 404 (4) to ground. Relay 422, however, does not energize at this time since it is shunted out by the direct circuit to ground closed at the armature and contact of the stepping relay 400. As soon as the brush 130 encounters the first metallic segment of the brush-selecting commutator, the stepping relay 400 deenergizes, and removing the shunt around relay 422, permits this relay to energize in series with relay 423. On the next energization of the stepping relay 400, as brush 130 reaches an insulated segment, the stepping circuit, closed at the armature and contact of relay 400, is extended by way of conductors 505 and 426, armature and front contact of relay 422, right-hand armature and contact of relay 420, winding of relay 421, to battery and ground. Relay 421 energizes and completes a circuit from battery through the windings of relays 421 and 420 in series, contact and armature of relay 421, contact 404 (4), to ground. As soon as stepping relay 400 is again short-circuited the shunt is removed from around the winding of relay 420 and this relay energizes in series with relay 421. The operation of the 0' counting relay 420 opens the fundamental circuit at its outer left-hand armature and closes at its inner left-hand armature a circuit including upper right-hand contact 407 (4), for driving the sender sequence switch 410 out of position 4 and into position 6. Sequence switch 410, passing from position 4 to position 6, opens at its contact 404, the locking circuit of the counting relays, permitting them to release. As soon following the energization of the 0' counting relay 420, as the brush 130 reaches the net insulating segment, relay 111 is deenergized and opens the circuit of the up-drive power magnet 127, terminating the movement of the brush shaft. Relay 111 also completes a circuit from battery through the winding of sequence switch magnet 110, upper left-hand contact 113 (6), upper right-hand contact 113 (6), back contact and left-hand armature of relay 111, upper left-hand contact 121 (2 to 17), lower right-hand contact 121 (1 to 12), to ground. Sequence switch 110 advances into position 7. A circuit is now closed from battery, through the winding of the brush-tripping magnet 128, upper and lower right-hand contacts 121, to ground. The magnet 128 energizes and prepares for the tripping of the selected set of brushes on the next upward movement of the brush shaft.

The fundamental circuit is again established from battery through the right-hand winding of relay 111, lower left-hand contact 118 (7), lower right-hand contact 118 (5 to 8) and thence as above traced, through the winding of the stepping relay 400, to ground at contact 403 closed in position 6. Relay 111 becomes energized and completes a circuit from battery, through the winding of sequence switch magnet 110, lower left-hand contact 112 (7), upper right-hand contact 112 (2 to 12), front contact and left-hand armature of relay 111, to ground at contact 121. Sequence switch 110 advances into position 8 while relay 111 remains locked up over its right-hand winding in the manner explained. Relay 111 closes a circuit from battery, through the winding of the up-drive power magnet 127, lower right-hand contact 112 (8), upper right-hand contact 112 (2 to 12), front contact and left-hand armature of relay 111 to ground at contact 121. Magnet 127 energizes and causes the brush shaft 129 to move, upward in the group selecting move-

ment. Each time the brush 130 engages a metallic segment of the group-selecting commutator 133, a circuit is closed from battery through the right-hand winding, contact 5 and inner right-hand armature of relay 111, upper left-hand contact 118 (3 to 10), upper right-hand contact 123 (7 $\frac{1}{4}$ to 8), commutator 133, brush 130, to ground. This circuit maintains the energization of relay 10 111 and at the same time shunts the stepping relay 400 in the fundamental circuit.

When relay 400 energizes in series with relay 111 a circuit is closed from ground through the contact and armature of relay 15 400, upper contact 402, (6), conductor 586 contact 514 of register 510 closed in position 2, conductor 515, and thence to conductor 427 (Fig. 4), armature and back contact of relay 424, winding of relay 425, to battery and ground. Relay 425 energizes and prepares a circuit for relay 424, which latter relay becomes energized as soon as the stepping relay 400 is shunted out by the group-selecting commutator of the switch. 20 For each group of terminals passed over by the brushes 142, 143 and 144, the stepping relay 400 is operated and a pair of counting relays energize and lock up. When the 0' counting relay 420 is finally energized, the fundamental circuit is opened and a circuit closed including the upper right-hand contact 407 (6) for driving the sender sequence switch into position 10. In passing from position 6 to position 10, contact 404 30 of sequence switch 410 is opened to permit the release of the energized counting relays. As soon after the opening of the fundamental circuit by the 0' counting relay 420, as the brush 130 engages an insulating seg-

40 ment of the commutator 133, relay 111 is de-energized. Relay 111 opens the circuit of power magnet 127, causing the switch to come to rest in operative relation to the desired group of terminals. Relay 111 also 45 closes a circuit from battery through the winding of sequence switch magnet 110, upper left-hand contact 113 (8), upper right-hand contact 113 (8), back contact and left-hand armature of relay 111, to ground at 50 contact 121. Sequence switch 110 moves out of position 8 and into position 9.

In position 9 of sequence switch 110, relay 111 is immediately energized by means of a circuit from battery, through the right-hand winding of said relay, lower left-hand contact 118 (9 to 9 $\frac{1}{2}$) upper left-hand contact 123 (9 to 9 $\frac{1}{4}$), to ground. Relay 111 completes a circuit from battery through the winding of sequence switch 110, lower left-hand contact 112 (9), upper right-hand contact 112 (2 to 12), front contact and left-hand armature of relay 111, to ground at contact 121, driving sequence switch 110 into position 10. Provided the first trunk in the 60 selected group, on the terminals of which the

brushes 142, 143 and 144 are now standing, is busy, relay 111 remains energized in the following circuit: battery, through the left-hand winding of said relay, contact 120 (9 to 10, front contact and outer right-hand armature of relay 111, upper left-hand contact 119 (2 to 11), upper right-hand contact 119 (9 to 16 $\frac{1}{4}$), test brush 144, test terminal 136 and thence to the multiple test terminal 136 at some other switch, brush 144 of such switch, upper right-hand contact 119 (9 to 16 $\frac{1}{4}$), lower left-hand contact 119 (10 $\frac{1}{4}$ to 18), to ground. Relay 111, by remaining energized, closes a circuit from battery through the winding of up-drive power magnet 127, lower right-hand contact 112 (10), upper right-hand contact 112 (2 to 12), front contact and left-hand armature of relay 111, to ground at contact 121. Magnet 127 is energized and brush shaft 129 moves upward in the trunk-hunting operation. When the test brush 144 encounters an idle test terminal, the holding circuit of relay 111 is opened and this relay releases its armatures to open the circuit of the power magnet 127. Relay 111 also closes a circuit from battery, through the winding of sequence switch magnet 110, upper left-hand contact 113 (10), upper right-hand contact 113 (10), back contact and left-hand armature of relay 111, to ground at contact 121. Sequence switch 110 moves out of position 10 and into position 11. Sequence switch 110, on reaching position 10 $\frac{1}{4}$, closes its lower left-hand contact 119 to supply a busy ground potential over test brush 144 to the test terminal 136 of the selected trunk. 90

In position 11 of sequence switch 110 the fundamental circuit is extended through to the office selector shown in Fig. 2 for controlling brush-selection at this switch. The fundamental circuit may be traced from battery through the right-hand winding of relay 211, lower left-hand contact 203 (1), left-hand contact 208 (1 to 4), conductor 200, terminal 134, brush 142, lower left-hand contact 123 (11), lower right-hand contact 118, (11), conductor 137, terminal 300, brush 305, upper contact 324 (10), winding of stepping relay 400, contact and outer left-hand armature of relay 420, upper right-hand contact 403 (10), lower right-hand contact 403 (10), upper contact 323 (10), brush 306, terminal 301, conductor 138, lower contact 125 (11), brush 143, terminal 135, conductor 201, contact 230 (1 to 4), to ground. Relays 211 and 400 become energized in this circuit. Relay 211 closes a circuit from battery, through the winding of sequence switch magnet 210, lower left-hand contact 204 (1), front contact and left-hand armature of relay 211, to ground. Sequence switch 210 moves from position 1 into position 2. Relay 211 remains energized in position 2 of sequence switch 210 by means of a circuit 100

from battery, through the right-hand winding, front contact and inner right-hand armature, outer right-hand armature and contact of said relay, lower right-hand contact 203 (1 to 4), and thence to ground as described. Relay 211 closes a circuit from battery through the winding of the up-drive power magnet 213, right-hand contacts 205 (2), front contact and left-hand armature 10 of relay 211, to ground. Magnet 213 energizes and causes the upward movement of the brush shaft 215 in the brush-selecting operation. For each brush-tripping position of the shaft 215, brush 218 engages a 15 metallic segment of the brush-selecting commutator 219. A circuit is thereby closed from battery, through the right-hand winding, front contact and inner right-hand armature of relay 211, outer right-hand armature and front contact of said relay, lower 20 right-hand contact 203 (1 to 4), upper right-hand contact 203 (1 $\frac{1}{4}$ to 2), commutator 219, brush 218, to ground. This circuit maintains the energization of relay 211 and causes 25 the stepping relay 400 in the fundamental circuit to be shunted.

When relay 400 first energizes in series with relay 211 a circuit is closed from ground, through the contact and armature 30 of relay 400, lower contact 401 (10), conductor 587, contact 524 of register 520 closed in position 2, conductor 525, and thence to conductor 427 (Fig. 4), armature and back contact of the No. 2' counting relay 424, 35 winding of relay 425, to battery and ground. Relay 425 becomes energized and prepares a locking circuit for itself in series with relay 424. When brush 218 encounters the first metallic segment of commutator 219, 40 the stepping relay 400 is shunted and relay 424 becomes energized. The stepping circuit closed at the armature and contact of relay 400 is now extended over the armature and front contact of relay 424 to the 45 next counting relay 423. When the proper number of brush-tripping positions have been passed over by the brush 218, the 0' counting relay 420 is energized to open the fundamental circuit. Relay 420 also closes 50 a circuit including its inner left-hand armature and contact and upper right-hand contact 407 (10) to drive sequence switch 410 into position 12. As soon after the fundamental circuit is opened by the 0' counting 55 relay, as brush 218 moves on to an insulating segment of commutator 219, relay 211 becomes deenergized. This closes a circuit from battery, through the winding of sequence switch magnet 210, lower right-hand 60 contact 204 (2), back contact and left-hand armature of relay 211 to ground. Sequence switch 210 advances from position 2 into position 3. In position 3 of sequence switch 210, a circuit is closed from battery through 65 the winding of the brush-tripping magnet

214, lower left-hand contact 206 (3 to 7), to ground. Magnet 214 energizes preparatory to tripping the selected set of brushes on the next upward movement of the shaft 215. 70

With sequence switch 210 in position 3 and sequence switch 410 in position 12 the fundamental circuit is again closed in the manner described for controlling the group-selecting operation of the office switch. Relay 211, upon energizing, closes a circuit from battery, through the winding of sequence switch magnet 210, lower left-hand contact 204 (3), front contact and left-hand armature of relay 211, to ground. Sequence 80 switch 210 advances into position 4, and relay 211 remains energized in the circuit leading through its right-hand armatures and the lower right-hand contact 203. Relay 211 completes a circuit from battery through 85 the winding of the up-drive magnet 213, right-hand contacts 205 (4), to ground at the front contact and left-hand armature of relay 211. The brush shaft 215 is moved upward and for each group of trunk terminals traversed the brush 218 engages a metallic segment of the group-selecting commutator 220. A circuit is thereby closed from battery, through the right-hand winding, front contact and inner right-hand armature of relay 211, outer right-hand armature and contact of relay 211, lower right-hand contact 203 (1 to 4), upper left-hand contact 203 (3 $\frac{1}{4}$ to 4), commutator 220, brush 218, to ground. This circuit holds the 90 relay 211 energized and causes the shunting of the stepping relay 400 in the fundamental circuit. 95

When relay 400 energizes in series with relay 211, with sequence switch 410 in position 12, a circuit is closed from ground, through the contact and armature of relay 400, upper contact 401 (12), conductor 588, contact 534 of register 530 closed in position 3, conductor 535, and thence to conductor 428 (Fig. 4), armature and back contact of the No. 3' counting relay 429, winding of the No. 3 relay 430, to battery and ground. Relay 430 attracts its armature and prepares a locking circuit for itself in series with the winding of relay 429. As the brush 218 encounters the first segment of the commutator 220, relay 400 is released to permit the energization of relay 429. On the next energization of stepping relay 400, the stepping circuit is extended by way of conductor 428, armature and front contact of relay 429, armature and back contact of relay 424, winding of relay 425, to battery and ground. In a similar manner the No. 2 counting relays and each following pair of counting relays are energized and locked up in response to the operation of stepping relay 400. When the 115 0' counting relay 420 is finally energized, 120 125 130

the fundamental circuit is opened and a circuit, including upper right-hand contact 407 (12), is closed, for driving sequence switch 410 out of position 12 and into position 14. As soon following the opening of the fundamental circuit at the sender, as brush 218 engages an insulating segment of commutator 220, the holding circuit of relay 211 is opened. Relay 211 releases its 10 armatures and opens the circuit of the up-drive power magnet 213, bringing the brushes 225, 226 and 227 to rest in operative relation to the selected group of outgoing trunks. Relay 211 also completes a 15 circuit from battery, through the winding of sequence switch magnet 210, lower right-hand contact 204 (4), back contact and left-hand armature of relay 211, to ground. Sequence switch 210 advances into position 20 5.

In position 5 of sequence switch 210, relay 211 is immediately energized in a circuit from battery through the left-hand winding of said relay, upper left-hand contact 229 (5 to 7), lower left-hand contact 229 (5), to ground. Relay 211 closes a 25 circuit from battery, through the winding of sequence switch magnet 210, lower left-hand contact 204 (5), front contact and 30 left-hand armature of relay 211, to ground, for driving sequence switch 210 out of position 5 and into position 6. Relay 211 remains energized in position 6 of the sequence switch, provided the first trunk in the 35 selected group is busy at this time. The holding circuit for relay 211 may be traced from battery through the right-hand winding, front contact and inner right-hand armature of said relay, outer right-hand 40 armature and contact of relay 211, upper left-hand contact 207 (5 to 18), upper right-hand contact 207 (5 to 6½), test brush 227, test terminal 224, and thence to a multiple of test terminal 224 at some other switch, 45 brush 227 of such other switch, to ground at the upper right-hand contact 206 (6½ to 8½). Relay 211, by remaining energized, completes a circuit from battery through 50 the winding of the up-drive power magnet 213, right-hand contact 205 (6), front contact and left-hand armature of relay 211, to ground. Switch shaft 215 is advanced upward in the trunk-hunting movement. When an idle trunk is reached the holding 55 circuit of relay 211 is opened, since no ground is found on the test terminal 224. The following substitute circuit, however, is maintained closed to prevent the immediate release of relay 211. Battery, through the 60 left-hand winding of said relay, upper left-hand contact 229 (5 to 7), upper right-hand contact 229 (5½ to 6), centering commutator 221, brush 216, to ground. This circuit is closed until the brushes 225, 226 65 and 227 are accurately centered on the ter-

minals of the idle trunk, at which time brush 216 engages an insulating segment of commutator 221. Relay 211 thereupon releases and opens the circuit of the up-drive power magnet 213. Relay 211 also 70 closes a circuit from battery, through the winding of sequence switch magnet 210, lower right-hand contact 204 (6), back contact and left-hand armature of relay 211 to ground. Sequence switch 210 advances 75 from position 6 into position 7. On reaching position 6½, sequence switch 210 closes its upper right-hand contact 206 to apply a busy ground potential to the test terminal 224 of the selected trunk. Relay 211 80 is again immediately energized by means of a circuit from battery, through its left-hand winding, upper left-hand contact 229 (5 to 7), lower left-hand contact 229 (7), to ground. Relay 211 completes a circuit 85 from battery through the winding of the sequence switch magnet 210, lower left-hand contact 204 (7), front contact and left-hand armature of relay 211 to ground. Sequence switch 210 advances into position 8. Relay 211 remains energized in position 8 of sequence switch 210 by means of a circuit from battery through the right-hand winding, front contact and inner right-hand armature of relay 211, outer right-hand 90 armature and contact of said relay, upper left-hand contact 207 (5 to 18), lower left-hand contact 207 (7 to 18), conductor 202, terminal 136, brush 144, upper right-hand contact 119 (9 to 16½), lower left-hand contact 119 (10½ to 18), to ground. The district and office switches having been positioned in the manner described a trunk circuit 700, 701 is selected leading to a 95 manual operator's position in the distant 100 office.

When the sender sequence switch 410 reaches position 14, after the completion of office group selection, a circuit is closed from ground, through contact 408 (14), upper 105 left-hand contact 316 (10), winding of sequence switch magnet 310, to battery and ground. Sequence switch 310 moves out of position 10 and into position 11. A circuit is now completed from battery through the 110 back contact and inner lower armature of relay 725, (Fig. 7), conductor 731, right-hand winding of relay 713, winding of relay 714, inner normal contact of relay 716, back contact and outer armature of relay 717, 115 back contact and outer armature of relay 708, conductor 700, terminal 222, brush 225, right-hand contact 208 (8), left-hand contact 208 (8) conductor 200, terminal 134, brush 142, lower left-hand contact 123 (11), 120 lower right-hand contact 118 (11), conductor 137, terminal 300, brush 305, lower contact 324 (11), upper contact 406 (14 to 14½), winding of relay 412, contact 413, (14 to 17), resistance 419, upper contacts 405, 14 to 125 130

14 $\frac{1}{2}$), lower contact 323 (11), brush 306, terminal 301, conductor 138, lower contact 125 (11), brush 143, terminal 135, conductor 201, upper contacts 209 (8), brush 226, terminal 223, conductor 701, inner armature and back contact of relay 708, inner armature and back contact of relay 717, outer normal contact of relay 716, left-hand winding of relay 713, to ground. Relay 713, being marginal, 5 does not energize in series with resistance 419. Relays 714 and 412, however, energize in the circuit traced. Relay 714 closes a circuit from ground, through its armature and contact, winding of relay 715, to battery 10 and ground. Assuming that plug 726 of the trunk circuit has not been removed from the jack by the operator after the termination of a prior call, relay 710 will be energized by means of a circuit to be hereinafter 15 described. Hence when relay 715 operates, it closes a circuit for itself from battery, through the winding and contact and inner left-hand armature of said relay, front contact and outer upper armature of relay 710, 20 back contact and inner left-hand armature of relay 712, to ground. Relay 715, at its right-hand armature and contact, shunts out the relay 714, permitting the latter relay to release. Relay 715 also closes a circuit from 25 battery, through the assignment lamp 711, outer right-hand armature and back contact of relay 705, right-hand armature and contact of relay 704, contact and outer left-hand armature of relay 715, to ground. The 30 illumination of lamp 711 informs the operator that a call is waiting on the corresponding trunk.

If, however, the plug 726 is not inserted in a line jack at the time the trunk 700, 701 35 is seized, relay 710 is deenergized and relay 715, finding no locking circuit, again releases as soon as relay 714 has been shunted out. Referring to Fig. 4, relay 412 which energized in series with relay 714 completes a 40 circuit from battery, through the winding of relay 411, armature and contact of relay 412 to ground. Relay 414 is energized at the same time by means of a circuit from battery, contact 415 (14 to 16), winding of 45 said relay, armature and contact of relay 412, to ground. Relay 411, at its lowermost armature and front contact, closes a circuit including contact 409 (14), for driving the sender sequence switch 410 out of position 50 14 and into position 16. As the sequence switch 410 reaches position 14 $\frac{1}{2}$, the circuit above-traced through the right-hand winding of marginal relay 713, over the upper or tip side of the line to lower contact 324, is now extended by way of lower contact 406 (14 $\frac{1}{2}$ to 16), innermost armature and front contact of relay 411, winding of relay 412, contact and armature of relay 414, front contact and middle armature of relay 411, 55 lower contact 405 (14 $\frac{1}{2}$ to 16), lower contact 323 (11), and thence over the ring side of the line to ground at the left-hand winding of marginal relay 713. It will be observed that the resistance 419 has been excluded from this latter circuit. Relay 713, therefore, becomes energized and completes a circuit from battery, through the winding of relay 712, to ground at the contact and armature of relay 713. Relay 712 closes a circuit in shunt of relay 714 as follows: 60 battery, back contact and inner lower armature of relay 725, conductor 731, right-hand winding of relay 713, contact and outer left-hand armature of relay 712, inner normal contact of relay 716, and thence over the tip side of the line and returning as described, to ground at the left-hand winding of relay 713. Relays 714 and 715, therefore, remain deenergized. Relay 712 completes a circuit from battery through 65 the assignment lamp 711, outer right-hand armature and back contact of relay 705, right-hand armature and contact of relay 704, contact and inner upper armature of relay 710, contact and inner right-hand armature of relay 712, to ground. The lamp 711 is illuminated and the operator, observing the same, knows that a call is awaiting 70 her attention.

At her convenience the operator responds 75 to the call by depressing the home assignment key 703 which is individual to the trunk 700, 701. The depression of key 703 operates to associate the trunk with the call 80 indicator mechanism at the home operator's 100 position. A circuit is closed from battery through the winding of relay 818, conductor 732, contact and outer lower armature of relay 710, right-hand winding of relay 705, contact of key 703, conductor 733, armature and contact of relay 823, back contact and right-hand armature of relay 821, to ground. Relay 705 energizes and locks up in a circuit from battery through the winding of relay 818, conductor 732, contact and outer lower 105 armature of relay 710, windings of relay 705, in series, contact and left-hand armature of said relay to ground. Relays 705 and 818, therefore, lock up independent of the key 703 which restores as soon as it is 110 released by the operator. Relay 705 closes a circuit from battery through the lamp 711, outer right-hand armature and front contact of relay 705, interrupter 734, to ground. Lamp 711 is caused to flash in the 115 circuit traced. Relay 705 also closes a circuit from battery through the winding of relay 708, contact and inner right-hand armature of relay 705, conductor 735, winding of relay 823, back contact and left-hand armature of relay 821, to ground. Relay 708 attracts its armatures and extends the 120 incoming trunk conductors 700 and 701 by way of conductors 736 and 737 to the operating relays 801, 800 and 802 of the call- 125 130

indicator mechanism. Up to this time, relay 412 at the sender has been energized in series with relay 713. When relay 708 attracts its armatures the battery supply 5 through the windings of relay 713 is disconnected from conductors 700 and 701 and relay 412 deenergizes. The release of relay 412 opens the circuits of relays 411 and 414, permitting these relays to become deenergized. Relays 713 and 712, at the trunk 10 circuit, are also deenergized at this time. Relay 411 completes a circuit from ground, through its lowermost armature and back contact, contact 416, (16), conductor 617, 15 left-hand contact 601 (1), winding of sequence switch magnet 610 to battery and ground. Sequence switch 610, which serves to transmit the code impulses to the distant office for setting the relay call-indicator, 20 leaves position 1 and advances in a continuous movement through position 7 and into position 17. The code impulses are sent to the indicator mechanism over a full metallic circuit comprising both sides of the 25 line in series. These impulses may be of either positive or negative polarity dependent upon which pole of battery is connected to a given side of the line. They may be also weak or strong, dependent upon whether 30 a high or low resistance is included in the circuit. Relay 801 is polarized in such a manner as to respond only to an impulse created by a flow of current from the positive pole of battery over the conductor 737 35 and returning to ground by way of conductor 736. The relay 800 is polarized in such a manner as to respond only to an impulse created by a flow of current in the opposite direction. Relay 802 responds to 40 strong impulses of both positive and negative polarity but, being marginal, does not operate on weak impulses.

When the impulse sequence switch 610 reaches position 1 $\frac{1}{4}$, a circuit is closed from 45 ground, which represents the positive pole of battery, upper contact 608 (1 $\frac{1}{4}$ to 2), conductor 620, back contact and inner armature of relay 411, lower contact 406 (14 $\frac{1}{2}$ to 16), lower contact 324 (11), and thence over 50 the upper or tip side of the line to conductor 736, windings of relay 801, 800 and 802 in series, conductor 737, and returning over the ring side of the line to lower contact 323 (11), lower contact 405 (14 $\frac{1}{2}$ to 16), middle armature and back contact of relay 411, conductor 621, upper contact 613 (1 $\frac{1}{4}$ to 2), high resistance 614, conductor 622, lower contact 418 (16), to the negative pole of battery. Owing to the high resistance 614, 55 this impulse is weak in character and is of such polarity as to cause the energization of relay 800. Relay 800 attracts its armature and closes a circuit from battery through the left-hand winding of relay 804, left-hand winding of relay 805, back contact and

left-hand armature of relay 804, contact and armature of relay 800, conductor 843, left-hand armature and contact of relay 818, contact and outer left-hand armature of relay 819 to ground. Relay 805 energizes and 70 closes a circuit from battery, through the left-hand winding of relay 804, left-hand winding of relay 805, right-hand winding of relay 804, contact and inner right-hand armature of relay 805, to the grounded conductor 843. Relay 804 however does not energize since its right-hand winding is shunted out at this time by the direct path through the armature and contact of relay 800 to the grounded conductor 843. Relay 805 75 closes a circuit from battery, through the winding of relay 808, back contact and inner armature of relay 807, contact and outer right-hand armature of relay 805 to the grounded conductor 843. Relay 808 attracts its armature and closes a circuit from battery through the windings of relays 808 and 807 in series, contact and inner right-hand armature of relay 808 to the grounded conductor 843. Relay 807, however, does 80 not energize since its winding is shunted out by the direct path to ground, through the contact and outer right-hand armature of relay 805. As soon as sequence switch 610 leaves position 2, relay 800 releases and 85 removes the shunt path from around the right-hand winding of relay 804. Relay 804 thereupon energizes in series with relay 805.

While sequence switch 610 passes through 90 positions 3 $\frac{1}{4}$ to 3 $\frac{1}{2}$ a circuit is closed from the positive pole of battery, upper contact 608 (3 $\frac{1}{4}$ to 3 $\frac{1}{2}$) conductor 620, thence over the tip side of the line through relays 801, 800 and 802, returning over the ring side of the line to conductor 621, upper contact 613 (3 $\frac{1}{4}$ to 3 $\frac{1}{2}$), high resistance 614, conductor 622 to the negative pole of battery at the contact 95 418. This causes another weak impulse to be sent of the proper polarity for energizing the polarized relay 800. Relay 800 attracts its armature and closes a circuit from battery through the left-hand winding of relay 804, front contact and left-hand armature of said relay, contact and armature of relay 800 to the grounded conductor 843. This direct circuit to ground shunts out the left-hand winding of relay 805 causing this relay to deenergize. Relay 805 releases its 100 armatures but a shunt circuit is maintained around the winding of relay 807 as follows: battery, through the winding of relay 808, back contact and inner armature of relay 807, contact and inner right-hand armature of relay 804 to the grounded conductor 843. When sequence switch 610 moves out of position 3 $\frac{1}{2}$, relay 800 releases its armature and opens the circuit through the left-hand winding of relay 804. Relay 805, being deenergized, no other circuit is offered for re- 105 110 115 120 125 130

lay 804 and consequently this relay becomes deenergized. When relay 804 releases its armatures the shunt is removed from around the winding of relay 807 and this relay energizes and locks up in series with relay 808.

When sequence switch 610 passes through positions $4\frac{3}{4}$ to 5, a circuit is closed from the positive pole of battery, through the upper contacts 608 ($4\frac{3}{4}$ to 5), conductor 620, thence 10 over the tip side of the line to conductor 736, through the windings of relays 801, 800 and 802, conductor 737, returning over the ring side of the line to conductor 621, lower contact 609 ($4\frac{3}{4}$ to 5), conductor 630, upper contact 15 545 (4), conductor 626, contact 632 (3 $\frac{1}{2}$ to 6), lower contact 603 (4 $\frac{3}{4}$ to 5), low resistance 616, conductor 633, upper contact 418 (16), to the negative pole of battery. The current flowing in this circuit is in such 20 a direction as to cause the energization of relay 800 and since only the low resistance 616 is included in the circuit, the impulse is strong in character. Therefore, marginal relay 802 becomes energized with relay 800. 25 Relay 800 closes a circuit from battery through the left-hand winding of relay 804, left-hand winding of relay 805, back contact and left-hand armature of relay 804, contact and armature of relay 800, to 30 grounded conductor 843. Relay 805 becomes energized and relay 804 remains deenergized. Relay 805 completes a circuit from battery, through the winding of relay 810, back contact and left-hand armature of relay 809, front contact and innermost armature of relay 35 807, contact and outer right-hand armature of relay 805, to the grounded conductor 843. Relay 810 attracts its armature and closes a circuit from battery through 40 the windings of relays 810 and 809, contact and inner right-hand armature of relay 810, to the grounded conductor 843. Relay 809, however, does not energize since its winding is shunted out by the direct path to ground, 45 through the contact and outer right-hand armature of relay 805. Relay 802 completes a circuit from grounded conductor 843, armature and contact of relay 802, outer right-hand armature and back contact of relay 804, outermost armature and contact of relay 807, inner right-hand armature and back contact of relay 809, conductor 825, 50 left-hand winding of relay 927, to battery and ground. Relay 927 becomes energized and closes a holding circuit for itself from battery through its two windings in series, contact and inner right-hand armature of said relay, conductor 844, inner right-hand armature and contact of relay 818, contact 55 and right-hand armature of relay 819, to ground. As sequence switch 610 passes out of position 5, the impulse circuit is opened and relays 800 and 802 become deenergized. Relay 800 removes the short-circuit from 60 around the right-hand winding of relay 804,

permitting this relay to become energized in series with relay 805.

In passing through positions $6\frac{1}{4}$ to $6\frac{1}{2}$ sequence switch 610 closes a circuit from the positive pole of battery through the upper contact 608 ($6\frac{1}{4}$ to $6\frac{1}{2}$), conductor 620, thence 70 over the tip side of the line to conductor 736, through the windings of relays 801, 800 and 802, conductor 737, returning by way of the ring side of the line, to conductor 621, upper contact 613 ($6\frac{1}{4}$ to $6\frac{1}{2}$), high resistance 614, conductor 622, lower contact 418 (16), to the negative pole of battery. The impulse transmitted in this circuit is weak in character and of such polarity as to cause the 80 energization of relay 800. Relay 800 closes a circuit from battery, through the left-hand winding of relay 804, front contact and left-hand armature of relay 804, contact and armature of relay 800, to the 85 grounded conductor 843, thus shunting out relay 805 which consequently becomes deenergized. The short-circuit around the winding of relay 809 is now maintained as 90 follows: Battery, through the winding of relay 810, back contact and left-hand armature of relay 809, front contact and innermost armature of relay 807, contact and inner right-hand armature of relay 904, to 95 grounded conductor 843. As sequence switch 610 moves out of position $6\frac{1}{2}$, the impulse circuit is opened and relay 800 releases its armature to open the circuit of relay 804. Relay 804 opens the shunt circuit 100 around the winding of relay 809, permitting this relay to energize in series with relay 810.

Sequence switch 610, in passing through positions $7\frac{3}{4}$ to 8, closes a circuit from the positive pole of battery, through the upper contact 608 ($7\frac{3}{4}$ to 8), conductor 620, thence 105 over the tip side of the line to conductor 736, windings of relays 801, 800 and 802, in series, conductor 737, returning over the ring side of the line to conductor 621, upper contact 613 ($7\frac{3}{4}$ to 8), high resistance 614, conductor 622, lower contact 418 (16), to the negative pole of battery. A weak impulse is transmitted in this circuit of the proper polarity for causing the energization of relay 800. Relay 800 again closes an energizing circuit for relay 805, relay 804 remaining deenergized as above explained. Relay 805 completes a circuit from battery, through the winding of relay 812, back contact and left-hand armature of relay 811, front contact and left-hand armature of relay 809, front contact and innermost armature of relay 807, contact and outer right-hand armature of relay 805, to ground at the conductor 843. Relay 812 attracts its armature and completes a circuit from battery through the windings of relays 812 and 811 in series, front contact and inner right-hand armature of relay 812, to the grounded conductor 843. Relay 811, however, does not energize since 110 115 120 125 130

its winding is shunted out by the relay 805. As sequence switch 610 leaves position 8, the impulse circuit is opened and relay 800 de-energizes to permit the energization of relay 5 804 in series with relay 805.

As sequence switch 610 passes through positions 8½ to 8¾ a circuit is closed from the positive pole of battery, through the lower contact 608 (8½ to 8¾) conductor 621, thence 10 over the ring side of the line to conductor 737, windings of relays 802, 800 and 801 in series, conductor 736, returning over the tip side of the line to conductor 620, upper contact 611 (8½ to 8¾), contact 612 (8¾ to 9), 15 conductor 631, contact 556 (4), conductor 625, lower contact 605 (6¾ to 9), upper contact 603 (7 to 8¾), high resistance 615, low resistance 616, conductor 633, upper contact 418 (16), to the negative pole of battery. 20 Since the circuit described includes the high resistance 615, the impulse transmitted is weak in character. Also the polarity is such as to cause the energization of polarized relay 801. Relay 801 completes a circuit from 25 grounded conductor 843, armature and contact of relay 801 left-hand armature and front contact of relay 805, outer right-hand armature and contact of relay 808, outer right-hand armature and contact of relay 30 810, outer right-hand armature and front contact of relay 812, outer right-hand armature and back contact of relay 814, conductor 830, left-hand winding of relay 929, to battery and ground. Relay 929 becomes 35 energized and closes a holding circuit for itself from battery, through its two windings in series, contact and inner right-hand armature of said relay, to the grounded conductor 844. As sequence switch 610 leaves 40 position 8¾, the impulse circuit is opened and relay 801 deenergizes.

Sequence switch 610, on passing through positions 9½ to 9¾, closes a circuit from the positive pole of battery through the upper 45 contact 608 (9½ to 9¾), conductor 620, thence over the tip side of the line to conductor 736, windings of relays 801, 800 and 802, conductor 737, and returning over the ring side of the line to conductor 621, upper contact 50 613 (9½ to 9¾), high resistance 614, conductor 622, lower contact 418 (16), to the negative pole of battery. A weak impulse is sent in this circuit of the proper polarity to 55 energize relay 800. Relay 800 closes a short circuit around the windings of relay 805, causing this latter relay to release. As sequence switch 610 moves out of position 9¾, relay 800 releases its armature to permit the deenergization of relay 804. When 60 relay 804 becomes deenergized, the short circuit which up to this time has been maintained around the winding of relay 811 as explained, is removed. Relay 811 thereupon energizes and locks up in series with relay 65 812.

When sequence switch 610 moves over positions 10 to 10½ a circuit is closed from the positive pole of battery, through the lower contact 608 (10 to 10½), conductor 621, over the ring side of the line to conductor 737, 70 windings of relays 802, 800 and 801, conductor 736, returning over the tip side of the line to conductor 620, upper contact 609 (10 to 10½), conductor 630, contact 565 (3), conductor 624, upper contact 605 (9¾ to 12), 75 upper contact 603 (10 to 11¾), high resistance 615, low resistance 616, conductor 633, upper contact 418 (16), to the negative pole of battery. Owing to the inclusion of high resistance 615, the impulse transmitted in 80 this circuit is weak in character and, therefore, does not cause the energization of relay 802. The polarity of the impulse, however, is such as to cause the energization of relay 801. Relay 801 closes a circuit from 85 grounded conductor 843, armature and contact of relay 801, left-hand armature and back contact of relay 805, left-hand armature and front contact of relay 808, left-hand armature and front contact of relay 90 810, left-hand armature and front contact of relay 812, outer left-hand armature and back contact of relay 814, conductor 831, left-hand winding of relay 934, to battery and ground. Relay 934 attracts its armatures and 95 closes a holding circuit for itself from battery through its two windings in series, contact and inner right-hand armature of said relay, to the grounded conductor 844.

As sequence switch 610 passes through positions 10½ to 11 a circuit is established from the positive pole of battery, through the upper contact 608 (10½ to 11), conductor 620, over the tip side of the line to conductor 736, windings of relays 801, 800 and 802, 100 conductor 737, over the ring side of the line, conductor 621, lower contact 609 (10½ to 11), conductor 630, contact 565 (3), conductor 624, upper contact 605 (9¾ to 12), lower contact 603 (10¾ to 11), low resistance 616, conductor 633, upper contact 418 (16), to the negative pole of battery. The impulse transmitted in this circuit is strong in character since only the low resistance 616 is included, and causes the energization of relay 105 802. Furthermore the polarity of the impulse is such as to cause the energization of relay 800. Relay 800 attracts its armature and closes the circuit described for the energization of relay 805. Relay 805 closes a 110 circuit from battery, through the winding of relay 814, back contact and left-hand armature of relay 813, front contacts and left-hand armatures of relays 811 and 809, front contact and innermost armature of relay 807, contact and outer armature of relay 805, to the grounded conductor 843. Relay 814 energizes and prepares a locking circuit for 115 itself in series with relay 813. As explained, however, relay 813 does not become energized. 120

125
130

gized as long as either of the relays 805 or 804 is operated. Relay 802 completes a circuit from grounded conductor 843, armature and contact of relay 802, outer right-hand 5 armature and back contact of relay 804, outermost armature and contact of relay 807, inner right-hand armature and front contact of relay 809, inner right-hand armature and front contact of relay 811, inner right-hand 10 armature and back contact of relay 813, conductor 832, left-hand winding of relay 935, to battery and ground. Relay 935 becomes energized and closes a holding circuit for itself from battery, through both of its 15 windings in series, contact and inner right-hand armature of said relay, to the grounded conductor 844. As sequence switch 610 leaves position 11, the impulse circuit is opened and relays 802 and 800 become de- 20 energized. Relay 800 removes the short-circuit from around the winding of relay 804, permitting this relay to become energized in series with relay 805.

Sequence switch 610, in moving from position 12 $\frac{1}{2}$ to 12 $\frac{3}{4}$ closes a circuit from the positive pole of battery through the upper contact 608 (12 $\frac{1}{2}$ to 12 $\frac{3}{4}$), conductor 620, over the tip side of the line to conductor 736, windings of relays 801, 800 and 802 in series, 25 conductor 737, returning over the ring side of the line to conductor 621, upper contact 613 (12 $\frac{1}{2}$ to 12 $\frac{3}{4}$), high resistance 614, conductor 622, to the negative pole of battery at contact 418. A weak impulse is therefore 30 transmitted of the polarity necessary to cause the energization of relay 800. Relay 800 closes a shunt circuit for causing the deenergization of relay 805. In moving out of position 12 $\frac{3}{4}$, sequence switch 610 opens the 35 impulse circuit and relay 800 releases. The release of relay 800 permits the deenergization of relay 804. Relay 804 opens the short-circuit from around the winding of relay 813 and this relay becomes energized in series 40 with relay 814.

When sequence switch 610 moves over positions 13 $\frac{1}{4}$ to 14 a circuit is closed from positive pole of battery, through the upper contact 608 (13 $\frac{1}{4}$ to 14), conductor 620, over the 45 tip side of the line to conductor 736, windings of relays 801, 800 and 802, conductor 737, over the ring side of the line to conductor 621, upper contact 613 (13 $\frac{1}{4}$ to 14), lower contact 613 (13 $\frac{1}{4}$ to 14 $\frac{1}{2}$), conductor 634, contact 55 575 (2), conductor 623, contact 604 (12 $\frac{1}{2}$ to 15), lower contact 603 (13 $\frac{1}{4}$ to 14), low resistance 616, conductor 633, to the negative pole of battery at contact 418. A strong impulse is transmitted in this circuit for energizing relay 802 and of the proper polarity to operate relay 800. Relay 800, in turn, causes the energization of relay 805 in the manner described. Relay 805 completes a 60 circuit from battery through the winding of relay 816, inner left-hand armature and con-

tact of relay 815, front contacts and left-hand armatures of relays 813, 811 and 809 in series, front contact and innermost armature of relay 807, contact and outer armature of relay 805 to the grounded conductor 70 843. Relay 816 energizes and prepares a locking circuit for itself in series with relay 815. Relay 815, however, remains deenergized so long as either relay 805 or 804 is operated. Relay 802 completes a circuit from 75 grounded conductor 843, armature and contact of relay 802, outer right-hand armature and back contact of relay 804, outermost armature and front contact of relay 807, inner right-hand armatures and front contacts of 80 relays 809, 811 and 813 in series, conductor 838, left-hand winding of relay 937, to battery and ground. Relay 937 attracts its armatures and closes a holding circuit for itself from battery, through its windings in 85 series, contact and inner right-hand armature of said relay to the grounded conductor 844. Sequence switch 610 leaves position 14 and relays 802 and 800 are deenergized. Relay 800, by releasing its armatures, permits the energization of relay 804.

Sequence switch 610, in passing from position 15 $\frac{1}{4}$ to 15 $\frac{3}{4}$, closes a circuit from the positive pole of battery, through the upper contact 608 (15 $\frac{1}{4}$ to 15 $\frac{3}{4}$), conductor 620, over 90 the tip side of the line to conductor 736, windings of relays 801, 800 and 802, conductor 737, ring side of the line, conductor 621, upper contact 613 (15 $\frac{1}{4}$ to 15 $\frac{3}{4}$), high resistance 614, conductor 622, to the negative pole of battery at contact 418. A weak impulse is transmitted in this circuit of a polarity to cause only relay 800 to become energized. Relay 800 closes a shunt circuit as above-described around the windings of relay 805, 100 causing this latter relay to deenergize. When sequence switch 610 leaves position 15 $\frac{3}{4}$, the impulse circuit is opened, relay 800 releases its armature and relay 804 in turn becomes deenergized. Relay 804 opens the shunt circuit around the winding of relay 815, permitting this relay to lock up in series 105 with relay 816.

The necessary code of impulses has thus been sent to the call-indicator mechanism 115 for selecting the proper thousands, hundreds, tens and units lamps to display before the operator the designation of the desired line, which, it will be recalled, is 4432. Since the relay 927 of the thousands group is energized the No. 4 thousands lamp 924 is illuminated in the following circuit: Battery, through the right-hand armature and upper contact of relay 817, conductor 840, inner right-hand armature and back contact of relay 939, left-hand armature and front contact of relay 927, inner left-hand armature and back contact of relay 940, lamp 924, front contact and outer right-hand armature of relay 927, outer left-hand 120 125 130

armature and contact of relay 940, back contact and outer right-hand armature of relay 941, conductor 847, lower contact and left-hand armature of relay 817, to the 5 grounded conductor 843. It will be observed that relay 817 is energized by means of a circuit closed at the inner left-hand armature and contact of relay 814. The circuit for the illumination of the No. 4 hundreds 10 lamp 926 may be traced from battery, through the right-hand armature and lower contact of relay 817, conductor 841, inner right-hand armature and back contact of relay 942, left-hand armature and back contact of relay 943, outer right-hand armature and back contact of relay 944, left-hand armature and front contact of relay 929, lamp 926, front contact and outer right-hand armature of relay 929, conductor 828, upper 15 contact and left-hand armature of relay 817, to the grounded conductor 843. The circuit for illuminating the No. 3 tens lamp 936 may be traced from battery, through the contact and outermost right-hand armature 20 of relay 816, conductor 842, inner right-hand armature and back contact of relay 945, left-hand armature and front contact of relay 935, inner left-hand armature and front contact of relay 934, lamp 936, back contact and inner left-hand armature of relay 945, to the grounded conductor 944. The circuit for the units lamp 938 may be traced from battery, outer right-hand armature and contact of relay 815, conductor 839, inner right-hand armature and back contact of relay 951, left-hand armature and front contact of relay 937, inner left-hand armature and back contact of relay 952, lamp 938, front contact and outer right-hand armature of 25 relay 937, outer left-hand armature and contact of relay 952, back contact and outer right-hand armature of relay 953, conductor 890, contact and inner right-hand armature of relay 815 to grounded conductor 843. 30 The sequence switch 610, after completing the transmission of the code impulse, comes to rest in position 17. In this position a circuit is established from ground, through contact 602 (17), conductor 635, upper right-hand contact 316 (11), winding of sequence switch magnet 310, to battery and ground. The trunk-finder sequence switch 310 thereupon moves out of position 11 into 35 position 13. In position 13 of sequence switch 310 a circuit is closed from ground, through the contact 313 (13), brush 308, terminal 303, conductor 145, left-hand contact 115 (11), right-hand winding of relay 111 to battery and ground. Relay 111 attracts 40 its armatures and completes a circuit from battery, through the winding of sequence switch magnet 110, lower left-hand contact 112 (11), upper right-hand contact 112 (2 to 12), front contact and left-hand armature of relay 111 to ground at contact 121. Sequence switch 110 thereupon moves into position 12. In this position the sequence switch 110 awaits the closure of the trunk circuit 100, 101, at the originating office. If the operator at the originating office has 45 already inserted the plug of her cord circuit in the jack of the outgoing trunk 100, 101, relay 102 is at this time energized. Since the circuits at the operator's position in the originating office are not disclosed in the present case, reference is made to an application of Lundell and Clark filed November 2, 1917, Serial No. 199,886, Patent No. 1,342,823, granted June 8, 1920, in which is shown and described in detail the manner of energizing the relay 102 in response to the closure of the trunk circuit by the originating operator. Relay 102, being energized, or as soon after the arrival of sequence switch 110 in position 12, as such relay is energized, a circuit is completed from ground through the armature and front contact of relay 103, right-hand contact 115 (12), right-hand winding of relay 111, to battery and ground. It will be noted that relay 103 is energized in response to the attraction of the armature of relay 102. Relay 111 closes a circuit from battery through the winding of sequence switch magnet 110, lower left-hand contact 112 (12), upper right-hand contact 112 (2 to 12), front contact and left-hand armature of relay 111 to ground at contact 121. Sequence switch 110 thereby advances into position 13 which is the talking position. Relay 111 releases as sequence switch 110 leaves position 12. 50 When sequence switch 110 moves out of position 12, it opens at its upper right-hand contact 114 the holding circuit of relay 311 at the trunk finder switch. Relay 311 releases and completes a circuit from ground through its left-hand armature and back contact, left-hand contact 315 (3 to 17), winding of sequence switch magnet 310, to battery and ground. Sequence switch 310 moves from position 13 into position 18. A circuit is now completed from battery, through the winding of the down-drive power magnet 319, contact 327 (18), to ground. Magnet 319 energizes and restores the trunk finder switch. In the normal position of the brush shaft 312 the projection 322 thereof engages and closes contact 321. A circuit is thereby completed from ground, through contact 321, left-hand contact 317 (18), winding of sequence switch magnet 310, to battery and ground. Sequence switch 310 moves into position 1 where a circuit is established from ground, through contact 325 (1), lower left-hand contact 407 (16), winding of sequence switch magnet 410 to battery and ground. By means of this circuit the sender sequence switch 410 is restored to its normal position 1. With 55 60 65 70 75 80 85 90 95 100 105 110 115 120 125 130

sequence switch 410 in position 1, a circuit is established from ground, through contact 417 (1), conductor 636, right-hand contact 601 (17 to 18), winding of sequence switch 5 magnet 610, to battery and ground. Sequence switch 610 thereupon moves out of position 17, through position 18 and into its normal position 1. The trunk-finder switch and associated register-sender apparatus 10 have thus been completely restored to their normal condition.

After the code impulses have all been sent and the last two progression relays 815 and 816 of the call-indicator mechanism have 15 been energized, a circuit is closed from ground, through the outer left-hand armature and contact of relay 815, contact and armature of relay 820, winding of relay 821, to battery and ground. Relay 821, at its 20 left-hand armature and back contact, opens the holding circuit for relay 708. Relay 708 becomes deenergized, disconnects the trunk conductors 700 and 701 from the impulse leads 736 and 737, and connects them 25 through to the left-hand side of the repeating coil 718. If the operator in the originating office has already inserted the plug of her cord circuit into the jack of the trunk, the outgoing end of such trunk is closed in 30 the manner shown in the above-mentioned application of Lundell-Clark, filed November 2, 1917, Serial No. 199,886, Patent No. 1,342,823, granted June 8, 1920. Relay 713 is, therefore, again energized in a circuit 35 from battery, through the back contact and inner lower armature of relay 725, conductor 731, right-hand winding of relay 713, winding of relay 714, inner normal contact of relay 716, back contact and outer armature of relay 717, back contact and outer 40 armature of relay 708, conductor 700 over the tip side of the line, as above traced to terminal 134 at the district selector, brush 142, right-hand contact 124 (12 $\frac{3}{4}$ to 16) 45 left-hand contact 124 (13), right-hand winding of relay 102, conductor 100, thence over the trunk circuit to the originating office and returning by way of conductor 101, left-hand winding of relay 102, upper 50 contact 125 (12 $\frac{3}{4}$ to 16), brush 143, terminal 135, over the ring side of the line to conductor 701, inner armature and back contact of relay 708, inner armature and back contact of relay 717, outer normal contact of relay 55 716, left-hand winding of relay 713 to ground. Relay 713 becomes energized and closes an operating circuit for relay 712 which, as explained, completes a shunt around the winding of relay 714. The operator, observing 60 the desired designation set up on the indicator lamps at her position seizes plug 726 of the trunk circuit, which she identifies by means of the flashing of the assignment lamp 711 individual to such circuit, and inserts it in the jack 727 of the called line. 65

The insertion of the plug in the jack completes a circuit from battery through the winding of relay 720, inner armature and back contact of relay 721, armature and contact of relay 722, outer right-hand armature 70 and contact of relay 712, winding of relay 725, sleeve of plug 726, sleeve of jack 727, winding of relay 724, to ground. A parallel branch of the circuit just traced extends through the winding of relay 721. Relay 721, being shunted out by the path through its inner armature and back contact and the armature and contact of relay 722, does not energize. Relays 720 and 725, however, become energized. Relay 725 establishes a 80 circuit from ground, through its outer lower armature and front contact and winding of relay 710. Relay 710 energizes and opens the circuits of relays 705 and 818. Relay 705 opens the circuit through the assignment 85 lamp 711, and interrupter 734, causing said lamp to be extinguished.

Relay 818 at its left-hand armature, opens the grounded connection to conductor 843, and at its inner right-hand armature removes ground from the conductor 844. Ground being removed from these conductors, all energized relays of the call-indicator mechanism, are immediately released, effacing the designation of the indicator 95 lamps. Relay 821 is also deenergized by the release of relay 815. The call indicator mechanism at the operator's position is now in condition to be associated with another 100 calling trunk circuit.

With relays 725 and 720 energized, a circuit is completed for the application of ringing current to signal the called subscriber. This circuit may be traced from the ringing source 723, through the winding of relay 722, front contact and lower armature of relay 720, ring of plug 726, ring of jack 727, over the loop of the called 105 sub-station 730, tip of jack 727, tip of plug 726, upper armature and front contact of relay 725, upper armature and front contact of relay 720, to ground. Relay 722 is marginal and does not energize while ringing current is being sent over the line. As soon as the called subscriber responds by 110 removing his receiver from the switchhook, the resistance of the line circuit is reduced in the well-known manner and relay 722 attracts its armature. Relay 722 opens the shunt path around the winding of relay 721, permitting this latter relay to become energized. Relay 721 closes a circuit from battery through its front contact and inner armature winding of said relay, and thence to ground through the winding of relay 115 724. This direct circuit from battery to ground shunts out the winding of relay 720 which relay releases its armatures, opens the ringing circuit and closes the tip and ring conductors of the trunk circuit. Talk- 120 125 130

ing current is supplied to the called line from battery, through the lower right-hand winding of repeating coil 718, winding of supervisory relay 719, back contact and lower armature of relay 720, ring of plug 726, ring of jack 727, over the loop of the called line, tip of jack 727, tip of plug 726, upper armature and front contact of relay 725, upper armature and back contact of relay 720, upper right-hand winding of repeating coil 718, to ground. Supervisory relay 719 energizes in this circuit and completes a circuit from battery through the winding of relay 716, contact and armature of relay 719, outer armature and contact of relay 721, to ground. Relay 716 attracts its armatures and reverses the connection of the windings of relay 713 to the tip and ring conductors 700 and 701, including the left-hand windings of repeating coil 718. Since relay 725 has been energized, talking current for the calling line is now supplied from battery through the front contact and inner lower armature of relay 725. The reversal of current over the trunk conductor 700 and 701 may serve to operate a supervisory signal at the originating operator's position to advise her that the called subscriber has answered.

In order to gain time in the handling of calls, the operator may assign the call-indicator mechanism to another calling trunk at the same time she is preparing to insert the plug 726, of the trunk shown, in the jack of the called line. As soon as she has made a mental note of the designation displayed on her indicator lamps pertaining to the trunk circuit shown, she seizes the plug 726, thereof and at the same time depresses the assignment key 703 individual to another calling trunk. The conductors 736, 737, 735, 733 and 732 are multiplied from the common call-indicator mechanism to each of the trunk circuits at the operator's position, as illustrated by the leads 848, 849, 850, 851 and 852, respectively. The operator, by depressing the assignment key 703 of a second trunk, prior to the insertion of plug 726 of the first trunk, completes a circuit from battery, through the winding of relay 818, multiple lead 852 outer lower armature of the relay 710 of the second trunk circuit, right-hand winding of the relay corresponding to relay 705, assignment key 703, multiple lead 851, armature and contact of relay 823, winding of relay 822, front contact and right-hand armature of relay 821, to ground. This circuit which includes only the right-hand winding of the relay 705 of the second trunk circuit, is of sufficiently low resistance to shunt down the relay 705 of the trunk circuit shown. Relay 705, therefore, opens the circuit of the assignment lamp 711 and also the circuit of the trunk closing relay 708.

When the operator releases the assignment key 703 of the second trunk, relay 705 of such trunk locks up through both its windings in series with relay 818. Where relay 818 has remained energized during the transition of the call-indicator mechanism from the first trunk to the second trunk some means must be provided to cause the release of the indicator relays and effacement of the lamps, before the second set of code impulses can be received. This is accomplished by the energization of relay 822 which in turn closes a circuit from battery, through the winding of relay 819, contact and armature of relay 822 to ground. Relay 819 attracts its armatures and opens the ground connection to conductors 843 and 844, thereby permitting the release of all the indicator relays which had been previously energized. The release of relay 815 causes, as explained, the deenergization of relay 821 and relay 821 in turn opens the energizing circuit of relay 822, permitting relay 819 to retract its armatures. Relay 821 also completes a circuit from ground, through its left-hand armature and back contact, winding of relay 823, multiple lead 850, through the inner right-hand armature and contact of the corresponding relay 705 of the second trunk circuit, winding of the corresponding relay 708, to battery and ground. Relay 708, therefore, energizes and closes the second trunk circuit through the indicator mechanism over multiple leads 848 and 849, ready for the transmission of the code impulses pertaining to the call thereon. The operator inserts the plug 726 of the trunk circuit shown in the jack of the called line and the connection is completed as already described.

Should the operator attempt to assign a second trunk to the call-indicator mechanism during the time that impulses are being sent to the indicator mechanism over the first trunk, no injurious effect is possible. As has been seen, the relay 821 remains deenergized until the call-indicator mechanism has been completely set. Relay 821 at its left-hand armature and back contact maintains the circuit described, through the winding of relay 823, conductor 735, and thence through the winding of relay 708 to battery and ground. Relay 823 maintains open the parallel circuits over multiples 851 to the assignment keys 703 of all other trunks. Hence the depression of an assignment key 703 of any other trunk does not close the circuit through the right-hand winding of the corresponding relay 705 to associate such trunk with the indicator mechanism.

At the termination of a conversation the called subscriber replaces his receiver on the switchhook and opens the circuit of the supervisory relay 719. Relay 719 releases

its armature to open the circuit of relay 716. Relay 716 becomes deenergized and reverses the direction of the flow of current over the trunk conductors 700, 701, to the originating office. This reversal of current flow serves in any well-known manner to inform the operator in the originating office that the called subscriber has hung up his receiver. The operator at the originating office 10 connects, by withdrawing the plug of her cord circuit from the jack of the outgoing trunk 100, 101. This act on the part of the operator serves to open the trunk circuit in the manner shown in the above mentioned 15 patent of Lundell and Clark. The opening of the trunk circuit at the originating office causes the release of relay 713 and consequently the deenergization of relay 712. During the time relay 712 is energized the 20 disconnect signal lamp 728 is shunted by a circuit from battery, either through the winding of relay 720, or through the front contact and inner armature of relay 721 and thence through the winding of relay 25 721, outer right-hand armature and contact of relay 712, to ground through the winding of relay 724. When, however, relay 712 becomes deenergized, this short-circuit is removed and lamp 728 is illuminated in a 30 circuit from battery, through said lamp, winding of relay 725, sleeve of plug 726, sleeve of jack 727, winding of relay 724, to ground. The operator, observing the 35 illumination of lamp 728, knows that the connection is no longer desired and removes plug 726 from the jack of the called line.

The opening of the trunk 100, 101, at the originating office, also permits the deenergization of relay 102 in the mechanical office. 40 Relay 102 opens the circuit of relay 103, which, in turn, completes a circuit from battery, through lamp 146, contact 107 (13), back contact and armature of relay 103, to ground. Lamp 146 is lighted to inform the 45 operator in the mechanical office that the district and office switches should be released. She thereupon depresses her disconnect key 106, establishing a circuit from battery, through the winding of relay 104, contacts 105 (12 to 17), key 106, to ground. Relay 104, becomes energized and completes a circuit from battery, through the winding of sequence switch magnet 110, contact 117 (12 to 17), contact and armature of relay 50 104, left-hand contact 116 (11 to 17), right-hand contact 116 (12 to 17), to ground. Sequence switch 110 leaves position 13 and advances into position 18. In this position a circuit is closed from battery through the 55 winding of the downdrive power magnet 126, lower right-hand contact 119 (18), lower left-hand contact 119 (10 to 18), to ground. Magnet 126 becomes energized and operates to restore the brush shaft 129.

With the brush shaft 129 in its normal 65 position a circuit is closed from ground, through the brush 130, contact 131, left-hand contact 109 (7 to 18), winding of sequence switch magnet 110, to battery and ground. Sequence switch 110 advances into 70 its normal position 1.

When sequence switch 110 leaves position 164 it opens, at its upper right-hand contact 119, the holding circuit of relay 211 at the office selector. Relay 211 becomes deenergized and completes a circuit from battery, through the winding of sequence switch magnet 210, lower right-hand contact 204 (8 to 17), back contact and left-hand armature of relay 211, to ground. Sequence 80 switch 210 moves from position 8 into position 18. In this position a circuit is closed from battery, through the winding of the downdrive power magnet 212, lower contacts 229 (18), to ground. Magnet 212 energizes 85 and operates to restore the brush shaft 215. When brush shaft 215 reaches its normal position a circuit is closed from ground, through brush 216, contact 217, upper right-hand contact 204 (3 to 18), winding of 90 sequence switch magnet 210, to battery and ground. Sequence switch 210 thereupon moves into its normal position 1.

Disposition of call by the adjacent operator. 95

A description will now be given of the operation when the adjacent operator in the terminating office attends to a call appearing at the home position. The operation of the switches in the mechanical office, the extension of the connection over trunk 700, 701, to the home operator's position, and the lighting of the assignment lamp 711 individual to such trunk take place in the same manner as that already described in detail. 100 The operator at the adjacent position shown in Fig. 10, observing that more calls are present at the home position than the operator thereat can conveniently handle, reaches across and depresses the team assignment 110 key 702 individual to trunk 700, 701, on which a call is awaiting attention. The team assignment key serves to associate the trunk 700, 701 at the home operator's position with the call-indicator mechanism at 115 the adjacent operator's position, diagrammatically illustrated below the horizontal broken line in Fig. 10. The depression of key 702 completes a circuit from battery, through the winding of relay 1018, corresponding to relay 818, conductor 1024, contact and inner lower armature of relay 710, right-hand winding of relay 704, key 702, conductor 1025, armature and contact of relay 1023, to ground at the contact and right-hand armature of relay 1021, corresponding to relay 821. Relay 704 becomes energized 120 and locks up in series with relay 1018 in a 125

circuit from battery, through the winding of relay 1018, conductor 1024, contact and inner lower armature of relay 710, windings of relay 704, contact and inner left-hand armature of said relay to ground. Relay 704, at its right-hand armature and front contact, closes a circuit to interrupter 738, causing the assignment lamp 711 to flicker. Relay 704 also completes a circuit from battery, through the winding of relay 717, contact and outer left-hand armature of relay 704, conductor 1026, winding of relay 1023, back contact and left-hand armature of relay 1021, to ground. Relay 717 attracts its armatures and connects the tip and ring conductors 700 and 701 over conductors 1027 and 1028 to relays 1000, 1001 and 1002 of the indicator mechanism at the adjacent operator's position. Relays 1000, 1001 and 1002 correspond respectively to relays 800, 801 and 802 and operate in response to the code impulses transmitted by the impulse sequence switch 610 to display the designation of the called line on the indicator lamps at the adjacent operator's position. The two switching relays 1004 and 1005, which respond to the operation of the polarized and marginal relays, and two pairs of progression relays 1007, 1008 and 1009, 1010, are diagrammatically illustrated in the drawings. When the call-indicator at the adjacent operator's position has been completely set, the operator thereat observes the designation displayed on her indicator lamps and, reaching across, seizes the plug 726 of the trunk circuit at the home operator's position and inserts it in the jack 727 of the called line. The insertion of the plug in the jack causes the operation of relays 725 and 710 in the manner already explained. Relay 710 opens the circuit of relays 704 and 1018. Relay 704 in turn opens the circuit of relays 717 and 1023. Relay 717 disconnects the tip and ring conductors 700 and 701 from conductors 1027 and 1028 leading to the adjacent operator's indicator mechanism and extends them to the left-hand windings of repeating coil 718. From this point on the application of ringing current to the called line and the reversal of current over the trunk in response to the called subscriber takes place precisely the same as when the call is attended to by the home operator. Moreover, supervision of the call and disconnection after conversation has been completed, remains under the control of the home operator.

Interrupter 738 operates at a higher frequency than interrupter 734, and when the assignment lamp 711 is interruptedly illuminated under control of interrupter 738 it is said to "flicker," whereas when it is under control of interrupter 734 it is said to "flash." The terms "flicker" and "flash" are,

therefore, used to differentiate between the rates of interruption of the assignment lamp. Accordingly, it will be seen that when team display key 702 is operated by a helping out operator at an adjacent position, the home assignment lamp 711 will flicker, thus indicating to the operators that the call on that particular trunk is being attended to by the helping out operator. This discriminatory provision is made to lessen the possibility of a home operator associating the trunk of an incoming call, which is being cared for by a helping out operator, with a number displayed at the time on the home operator's indicator. Such a contingency might arise where a helping out operator depresses a team display key and does not immediately pick up the plug associated therewith.

The trunk terminating in plug 1013 at the operator's position shown in Fig. 10, is identical in all respects to the trunk shown in detail at the operator's position in Fig. 7. Calls are extended to this operator's position over trunk conductors 1011 and 1012 from the office selector switch in the mechanical office. The trunk circuits at the operator's position shown in Fig. 10 are similarly arranged to enable this operator to be assisted by the adjacent operators during the periods she is confronted with an excessive number of calls. The trunk circuit shown in Fig. 10 may be so arranged that the operator whose position is shown in Fig. 7 acts as the helping out operator for calls appearing on this trunk. Therefore, the conductors 1030, 1031, 1032, 1033 and 1034 may be connected by way of multiple leads, such as 848, 849, 850, 851 and 852 to the indicator mechanism at the operator's position shown in Fig. 7. In like manner, the conductors 1030, 1031, 1032, 1033 and 1034 belonging to other trunks at the operator's position shown in Fig. 10, would be connected to the indicator mechanism at the other adjacent operator's position (not shown). By this arrangement the calls appearing on a portion of the trunks at any given operator's position may be attended to by one of the operators adjacent to such position, while calls appearing on the remaining trunks at such given position may be handled by the adjacent operator on the other side thereof.

While only a few connections are shown between the contacts of the impulse switch 610 and the contacts of the numerical registers 540, 550, 560 and 570, this is sufficient to give a clear understanding of the operation of the indicator mechanism for the called number assumed. It is obvious that the necessary sets of code impulses may be transmitted to operate the indicator mechanism in accordance with any desired series of digits. To obtain the required code of

impulses as determined by the set positions of the numerical registers, it is only necessary to wire the corresponding contacts of these registers to the proper contacts of the 5 impulse sequence switch 610.

What is claimed is:

1. In a telephone system, an operator's position, a trunk circuit incoming to said position, an indicating device at the said position, means controlled at said position for associating said indicating device with said trunk, means operated over said trunk for setting the indicating device, a second operator's position, an indicating device thereat, 10 means for associating the indicating device at said second position with said trunk, and means operated over said trunk for setting the indicating device at said second position.
2. In a telephone system, an operator's position, a trunk circuit incoming to said position, an indicating device at said position, means controlled at said position for associating said indicating device with said trunk, means operated over said trunk for 15 setting the indicating device, a second operator's position, an indicating device thereat, means controlled at said first position for associating the indicating device at said second position with said trunk, and means operated over said trunk for setting the indicating device at said second position.
3. In a telephone system, an operator's position, a trunk circuit incoming to said position, means for extending a connection to 20 the operator's position over said trunk, an indicating device at said position, means controlled at said position for associating said indicating device with said trunk, means operated over said trunk for setting the indicating device, a second operator's position, an indicating device thereat, means for associating the indicating device at said second position with said trunk, means operated over said trunk for setting the indicating device at said second position, and means operable by the operator at either position 25 for further extending said connection.
4. In a telephone system, an operator's position, a trunk circuit incoming to said position, an indicating device at said position, means controlled at said position for associating said indicating device with said trunk, means for sending current impulses over said trunk, means responsive to said 30 impulses for setting the indicating device, a second operator's position, an indicating device thereat, means for associating the indicating device at said second position with said trunk, and means responsive to impulses sent over said trunk for setting the indicating device at said second position.
5. In a telephone system, an operator's position, a trunk circuit incoming to said position, an indicating device at said position, means for associating the indicating 35

device with said trunk, means responsive to the association of the indicating device with said trunk for sending current impulses over said trunk, means operated by said impulses for setting said indicating device, a second operator's position, an indicating device thereat, means for associating the indicating device at said second position with said trunk, and means operated by impulses sent over said trunk for setting the 40 indicating device at said second position.

6. In a telephone system, an operator's position, a trunk circuit incoming to said position, an indicating device at said position including a plurality of designation 45 lamps, means controlled at said position for associating the indicating device with said trunk, means operable over said trunk for selecting variable combinations of said lamps, a second operator's position, an indicating device thereat, means for associating the indicating device at said second position with said trunk, and means operable over said trunk for selecting variable combinations of the lamps of the indicating device at said second position.

7. In a telephone system, an operator's position, a trunk circuit incoming to said position, an indicating device at said position including a plurality of designation 50 lamps, means for associating the indicating device with said trunk, means for sending variable codes of impulses over said trunk, means responsive to said impulses for selecting variable combinations of said lamps, a second operator's position, an indicating device thereat, means for associating the indicating device at said second position with said trunk, and means responsive to the code impulses sent over said trunk for selecting variable combinations of the lamps of the indicating device at said second position.

8. In a telephone system, an operator's position, a plurality of trunk circuits incoming to said position, an indicating device at said position common to said trunks, means controlled at said position for associating the indicating device with one of said trunks, means operated over said trunk 55 for setting said device, a second operator's position, an indicating device thereat, means for associating the indicating device at said second position with said trunk, and means operated over said trunk for setting the indicating device at said second position.

9. In a telephone system, two operators' positions; two trunk circuits, one incoming to each position; an indicating device at each of said positions; means controlled by the operators for associating either indicating device with either of said trunks; and means operated over either of said trunks for setting the indicating device associated therewith.

10. In a telephone system; two operators' positions; two trunk circuits, one incoming to each position; an indicating device at each position; means controlled by the operators for associating either indicating device with either of said trunks; means for sending impulses over said trunks; and means responsive to the impulses sent over either trunk for setting the indicating mechanism associated therewith. 10
11. In a telephone system, two operators' positions, a plurality of trunk circuits incoming to each of said positions, an indicating device at each position, means controlled by either operator for associating either of said indicating devices with any one of the trunks at either of said positions, and means operated over any of said trunks for setting the indicating device associated with such 15 trunk. 20
12. In a telephone system, an operator's position, a trunk circuit incoming to said position, an indicating device at said position, means at said position for associating the indicating device with said trunk, means operated over said trunk for setting the indicating device, a second operator's position, an indicating device thereat, means at the first operator's position for associating the 25 indicating device at said second position with said trunk, and means operated over said trunk for setting the indicating device at said second position. 30
13. In a telephone system, an operator's position, a trunk circuit incoming to said position, an indicating device at said position, means for sending impulses over said trunk, means at said position for directing said impulses to the indicating device to 35 variably operate the same, a second operator's position, an indicating device thereat, and means at the first operator's position for directing the impulses sent over said trunk to the indicating device at said second position to variably operate the same. 40
14. In a telephone system, an operator's position, a trunk circuit incoming to said position, an indicating device at said position, an assignment key for associating said 45 device with said trunk, means operated over said trunk for setting the indicating device, a second operator's position, an indicating device thereat, a second assignment key for associating the indicating device at said 50 second position with said trunk, and means operated over said trunk for setting the indicating device at said second position. 55
15. In a telephone system, an operator's position, a trunk circuit incoming to said position, an indicating device at said position, an assignment key at the operator's position, individual to said trunk, for associating the indicating device with said 60 trunk; means operated over said trunk for setting the indicating device; a second 65
- operator's position; an indicating device thereat; a second assignment key at the first position, individual to said trunk, for associating the indicating device at said second position with said trunk; and means operated over said trunk for setting the indicating device at said second position. 70
16. In a telephone system, an operator's position, a trunk incoming to said position, an indicating device at said position, a connecting relay for connecting the indicating device to said trunk, means operated over said trunk for setting the indicating device, a second operator's position, an indicating device thereat, a connecting relay for connecting the indicating device at said second position to said trunk, and means operated over said trunk for setting the indicating device at said second position. 75
17. In a telephone system, an operator's position, a trunk circuit incoming to said position, an indicating device at said position, a connecting relay for connecting the indicating device to said trunk, means operated over said trunk for setting the indicating device, a second operator's position, an indicating device thereat, a connecting relay for connecting the indicating device at said second position with said trunk, means operated over said trunk for setting the indicating device at said second position, and means at said first operator's position for operating said relays. 80 90
18. In a telephone system, an operator's position, a trunk circuit incoming to said position, automatic switches for extending a connection over said trunk to the operator's position, an indicating device at said position, means controlled at said position for associating said indicating device with said trunk, means operated over said trunk for setting the indicating device, a second operator's position, an indicating device thereat, means controlled at said first position for associating the indicating device 95 at said second position with said trunk, means operated over said trunk for setting the indicating device at said second position, and means for further extending said connection. 100 105 110
19. In a telephone system, an operator's position, a trunk circuit incoming to said position, an indicating device at said position, means for associating said indicating device with said trunk, means operated over the talking conductors of said trunk for setting the indicating device, a second operator's position, an indicating device thereat, means for associating the indicating device at said second position with said trunk, and means operated over the talking conductors of said trunk for setting the indicating device at said second position. 115 120
20. In a telephone system, a trunk, a plurality of mechanisms each of which is oper- 125 130

able over said trunk, means for extending said trunk to any one of said mechanisms individually, and a signal operable in response to the operation of said means for indicating to which of said mechanisms said trunk is extended.

21. In a telephone system, a trunk, a plurality of mechanisms each of which is operable over said trunk, means for extending any one of said mechanisms to said trunks individually, a signal, and means responsive to the operation of said first means for operating said signal in a plurality of ways for indicating to which of said mechanisms said trunk is extended.

22. In a telephone system, a trunk, a plurality of mechanisms each of which is operable over said trunk, means for extending said trunk to any one of said mechanisms individually, a signal, and means responsive to the operation of said first means for intermittently operating said signal at different frequencies for indicating to which of said mechanisms said trunk is extended, there being a different frequency corresponding with each of said mechanisms.

23. In a telephone system, a trunk, a plurality of mechanisms each of which is operable over said trunk, means for extending said trunk to any one of said mechanisms individually, a lamp signal operable in response to the operation of said means, a circuit and source of current for said lamp signal, and means for interrupting said circuit at different frequencies dependent upon which of said mechanisms is connected with said trunk, there being a different frequency of operation corresponding with each of said mechanisms.

24. In a telephone system, a trunk, two operators' positions, an indicator at each of said positions, means operable to extend said trunk to either of said indicators, and a signal responsive to the operation of said means for showing to which of said indicators said trunk is extended.

25. In a telephone system, two operators' positions, a trunk incoming to one of said positions, a signal associated with said trunk, an indicator at each of said positions, means for extending said trunk to either of said indicators, and means responsive to the operation of said first mentioned means for causing said signal to indicate to which of said indicators said trunk has been extended.

26. In a telephone system, two operators' positions, a trunk incoming to one of said positions, an indicator at each of said positions, a signal associated with said trunk, a key for extending said trunk to one of said indicators, a second key for extending said trunk to the other of said indicators, and means responsive to the operation of either of said keys to effect a distinctive operation

of said signal for indicating to which of said indicators said trunk is extended.

27. In a telephone system, two operators' positions, a trunk incoming to one of said positions, means whereby incoming calls on said trunk may be extended by an operator at either of said positions, a signal, means operable to cause said signal to operate in one characteristic manner to indicate that the operator at one of said positions has undertaken to extend an incoming call on said trunk, and means operable to cause said signal to operate in a different characteristic manner to indicate that the operator at the other position has undertaken to extend the call.

28. In a telephone system, two operators' positions, a trunk incoming to one of said positions, means whereby incoming calls on said trunk may be extended by an operator at either of said positions, signaling means operable to indicate that the operator at one of said positions has undertaken to extend an incoming call on said trunk, and other signaling means operable to indicate that the operator at the other position has undertaken to extend the call.

29. In a telephone system, two adjacent operators' positions, a trunk incoming to one of said positions, an indicator at each of said positions, a signal individual to said trunk, a key for extending said trunk to one of said indicators, a second key for extending said trunk to the other of said indicators, means responsive to the operation of said first mentioned key for causing said signal to operate interruptedly at a certain frequency, and means responsive to the operation of said second key for causing said signal to operate interruptedly at a frequency different from the first mentioned frequency.

30. In a telephone system two adjacent operators' positions, a trunk incoming to one of said positions, an indicator at each of said positions, a lamp signal individual to said trunk, a key for extending said trunk to one of said indicators, a second key for extending said trunk to the other of said indicators, means responsive to the operation of said first mentioned key for causing said lamp signal to flash, and means responsive to the operation of said second key for causing said lamp signal to flicker.

31. In a telephone system, two adjacent operators' positions, a trunk incoming to one of said positions, an indicator at each of said positions, a lamp signal individual to said trunk, a circuit and source of current for said lamp signal, a key for extending said trunk to one of said indicators, a second key for extending said trunk to the other of said indicators, a low frequency circuit interrupter, a high frequency circuit interrupter, means operable in response to the operation

of said first key for connecting said low frequency interrupter in said circuit, and means operable in response to the operation of said second key for connecting said high frequency interrupter in said circuit.

32. In a telephone system, an operator's position, a trunk circuit incoming to said position, an indicating device at the said position, means controlled at said position for operatively associating said indicating device with said trunk, means operable for setting said indicating device, a signal at said position operable in a characteristic manner for informing the operator at the position of an incoming call on said trunk awaiting attention, and means for causing said signal to operate in a second characteristic manner, said last mentioned means being operable in response to an operation of said first mentioned means.

33. In a telephone system, an operator's position, a trunk circuit incoming to said position, an indicating device at the said position, means controlled at the said position for operatively associating said indicating device with said trunk, means operable for setting said indicating device, a lamp signal at said position, means operable to cause said lamp signal to burn steadily to indicate an incoming call on said trunk

awaiting attention, and means responsive to the operation of said first mentioned means for causing said lamp signal to burn intermittently.

34. In a telephone system, an operator's position, a trunk circuit incoming to said position, an indicating device at the said position, means controlled at the said position for associating said indicating device with said trunk, a signal, means responsive to the operation of said first mentioned means for causing said signal to operate in a characteristic manner, means operable for setting the indicating device, a second operator's position, an indicating device thereat, means for associating the indicating device at said second position with said trunk, means responsive to the operation of said last mentioned means for causing said signal to operate in a second characteristic manner distinguishable from the characteristic manner first mentioned, and means operable for setting the indicating device at said second position.

In witness whereof, I hereunto subscribe my name this 4th day of June, A. D., 1920.

ALBEN E. LUNDELL.

In witness whereof, I hereunto subscribe my name this 7th day of June, A. D., 1920.

EDGAR H. CLARK.
